REFRIGERATION PLATE COOLING UNIT

Richard H. Swart, Utica, N. Y., assignor to Savage Arms Corporation, Utica, N. Y., a corporation of New York

Application March 14, 1946, Serial No. 654,380

1 Claim. (Cl. 62—126)

1
My invention relates to refrigeration plate cooling units, and I declare the following to be a full, complete, concise and exact description thereof sufficient to enable anyone skilled in the art to which it appertains to make and use the same, reference being had to the accompanying drawings in which like reference characters refer to like parts throughout the specification.

The object of the invention is to provide a refrigerant unit employing two or more refrigerant plates connected in series in such manner that the gaseous portion of the refrigerating mixture is allowed to by-pass the refrigerant circuit in the plates, whereby the refrigerant circulates with negligible pressure drop. It is important that there be negligible pressure drop in the circuit in order to maintain a temperature uniformity throughout the series of refrigeration plates. Furthermore, low pressure drop is conducive also to high thermodynamic efficiency of the complete system.

Heretofore, there has been in use the conventional continuous or "serpentine" refrigerant circuit similar to continuous pipe coils, and also the trapped or "flooded" circuit. The continuous type has the advantage of providing positive oil return by avoiding a building up of oil concentration in the refrigerant due to the high velocity of the vapor, whereas the flooded or trapped type has the advantage of high heat transfer for the reason that the interior surfaces of the plates used are covered with almost solid liquid refrigerant. The continuous type has a very low heat transfer due to the small quantity of liquid in contact with the metal of the plate. The flooded type tends to concentrate oil in the refrigerant and portions of the plates tend to become oil logged.

Moreover, in a refrigeration apparatus having a multiple plate circuit comprising a compressor, condenser and evaporator, the required evaporator surface to effect refrigeration must be relatively great and thereby requires great length of conduit, which causes pressure drop in the expanding refrigerant circuit.

The present invention combines the merits of both the continuous and flooded or trapped types by providing a by-pass in each plate, whereby the vapor in the refrigerant mixture is short circuited and reunited with the refrigerant unevaporated liquid and the mixture allowed to proceed through its course in the refrigerant plates connected in series.

The apparatus is self cleaning in regard to objectional oil concentration in the refrigerant, for

2

the reason that the unevaporated liquid carries the oil in solution through the plates arranged in series.

The object will be understood by referring to the drawings in which:

Fig. 1 is a perspective view of the refrigeration unit.

Fig. 2 is an elevational view of one of the plates in the unit.

Fig. 3 is a sectional view taken on the line 3—3 of Fig. 2.

Referring more particularly to the drawings, the present apparatus employs several refrigerant plates designated 1, 2 and 3, which are made preferably by uniting two sheets of metal 4 and 5 and welding them together at the outer or marginal edges as at 6. Sheet 4 is embossed to form with sheet 5 used as a back wall a continuous passageway 10 therethrough for the circuit of the refrigerant.

This continuous passageway 10 of each of the several plates 1, 2 and 3 has respectively an inlet fitting 11, a lower horizontally disposed manifold 15 located near the bottom portion of each of said plates 1, 2 and 3 and vertically disposed conduits 16, 17, 18 and 19. Said vertical conduits 17, 18, and 19 are connected at their upper ends with outlet manifold 20 disposed in parallel relation to manifold 15. A fitting 21 is formed or attached to plate 1 at the location of the outlet of manifold 20 for the attachment of connecting pipe 22. The opposite end of pipe 22 has a similar attachment to plate 2.

A by-pass conduit 24 disposed at an angle and having a predetermined cross sectional area joins the upper part of conduit 16 with the left hand end of the conduit of outlet manifold 20, whereby to allow the vapor in the refrigerant to be short circuited from conduit 16 to manifold 20 without passing down with the refrigerant liquid through conduit 16 to manifold 15.

Manifolds 15 and 20 and vertical pipes or conduits 16, 17, 18 and 19 operate together as a flooded refrigeration circuit for the reason that they are nearly completely liquid filled. They are designed, however, to minimize liquid volume and thus oil concentration in the refrigerant.

Plate 2 is made similar to plate 1 and is disposed in reverse relation thereto with its inlet at the end opposite to that of plate 1. It has an inlet header 25, a lower manifold 26, vertical risers or conduits 27, 28, 29 and 30, an outlet manifold 31, and a by-pass conduit 32, whereby to allow for the short circuit of the vapor. It has

also a nipple 33 for the attachment of connecting pipe 22.

Likewise plate 3 is similar to plate 1 and is disposed in the same position with respect thereto, it has an inlet header 35, a lower manifold 36, vertical risers or conduits 37, 38, 39 and 40, an upper outlet manifold 41 and a by-pass conduit 42 connecting the upper portion of conduit 37 with outlet manifold 41. It is attached to plate 2 by connecting pipe 43 at the end opposite to connecting pipe 22.

Plate 3 is joined to accumulator plate 45, made similar to plates 2 and 3, except it has no by-pass conduit. It is bent at right angles to itself at 46. There is an inlet manifold 47, a lower manifold 48 and connecting conduits 50. Manifold 47 is connected to compressor 51 by a pipe 52, which in turn is connected by a pipe 53 of much smaller diameter than pipes 22, 43 and 52 to condenser 55 and thence to high side float valve 56. Valve 56 is connected to dehydrator 57 by pipe 58 of the same diameter as pipe 53. Said dehydrator 57 is connected to plate 1 by pipe 60 which has a very small calibrated diameter to restrict the liquid flow to a predetermined degree.

Pipe 60 is attached to the coiled part 61 of suction pipe 52, whereby to aid in cooling the refrigerant passing therethrough, thereby utilizing the sensible cooling effect of the cold suction vapor passing through said pipe 61.

The operation of the apparatus is effected by compressor 51 forcing the refrigerant through the system. From compressor 51, the refrigerant passes through pipe 53 to condenser 55 where the refrigerant is liquefied. A fan 54 will aid in cooling condenser 55 which is kept warm due to the liberation of heat of the refrigerant returning to a liquid body. From condenser 55 the refrigerant will pass to high side float valve 56 which admits the condensed refrigerant liquid to the dehydrator 57. Said dehydrator 57 absorbs any water from the refrigerant and thence it passes on through restrictor pipe 60 to coil 61. The high pressure warm refrigerant liquid in pipe 60 will be cooled by the returning cold vapor in pipe 52 at coil 61. In passing through restrictor pipe 60, the pressure is reduced and a portion of the liquid evaporates, whereby the refrigerant becomes a mixture of liquid and vapor.

This refrigerant mixture of liquid and vapor will enter fitting 11 of plate 1. The liquid portion of the refrigerant mixture will flow down by its own velocity aided by gravity through conduit 16 past by-pass conduit 24 into lower manifold 15, whence it will rise through vertical conduits 17, 18 and 19 to outlet manifold 20. As said refrigerant rises in conduits 17, 18 and 19 it will partially evaporate thereby absorbing heat to cause refrigeration.

In the meantime, while the refrigerant liquid and the vapor generated from the boiling liquid is passing upwards through conduits 17, 18 and 19, the vapor portion entering plate 1 will have escaped through by-pass 24 to outlet manifold 20 and rejoin the vapor generated in conduits 17, 18 and 19 at manifold outlet 20. This mixture of vapor and liquid passes on to plate 2.

This same process will happen as the refrigerant passes through plates 2 and 3. When the refrigerant mixture, however, comes to accumulator plate 45, the refrigerant liquid will be separated from the vapor which will be sucked through pipe 61 back to compressor 51.

By thus allowing the vapor to escape through the several by-passes 24, 32 and 42 of the system, the pressure drop throughout the apparatus or unit as a whole will be negligible. This is extremely important in maintaining temperature uniformity throughout the system as well as conducive to good thermodynamic efficiency due to low pressure drop in plates 1, 2 and 3 or the unit as a whole.

In order to effect the above mentioned uniformity of temperature throughout the system, it is necessary to prevent the accumulation of oil in the vertical conduits in plates 1, 2 and 3. In usual refrigeration systems, a small quantity of oil pumped through the compressor 51 circulates with the liquid refrigerant. This oil is non-volatile and therefore tends to accumulate in any part of the refrigeration evaporator plates 1, 2 and 3 which is not swept through, either by positively circulated liquid refrigerant or by high velocity vapor. A vertical conduit, sealed at its lower end is particularly liable to become "oil-logged" for the above reasons. Special means of preventing this condition, herein described will prevent this accumulation of oil, which obviously result in that portion of the evaporator plates 1, 2 or 3 warming above the desired temperature due to lack of refrigerating liquid feed. If, however, a multiplicity of vertical conduits are provided with a horizontal conduit connecting them at their lower ends, the incoming liquid refrigerant, being heavier than the oil, will displace the oil upwardly, both by reason of the greater density of the refrigerant, and also by the boiling action, and vapor generation of the refrigerant. If each conduit were fed a sufficiency of liquid refrigerant to completely vaporize it, it should be necessary to depend upon the vapor velocity alone to remove the accumulation of oil in the conduit, and it might be possible to build up an accumulation of a high percentage of oil in the liquid refrigerant lower in the vertical conduit. It has been found, however, that if each vertical conduit is provided with an excess of liquid refrigerant over and above that required for cooling that section of the plate, there is no tendency of oil to either increase appreciable in concentration in the liquid refrigerant, or to completely oil log the conduit.

More specifically as the refrigerant liquid passes downwardly in conduit 16 of plate 1 by the vapor by-pass 24, it establishes an essentially static head of solid refrigerant liquid in conduit 16 of plate 1, whereas any vapor formed in said conduit 16 bubbles upward through conduit 16 and passes out through by-pass 24, conduit 20 and pipe 22 to the next plate 2.

The refrigerant liquid passing downwardly in conduit 16 continuously replaces the evaporating liquid in conduits 17, 18 and 19. Moreover, the refrigerant liquid is supplied to the conduits in plate 1 in excess of that required for complete vaporization and for this reason the surplus liquid together with the by-passed vapor, and the vapor formed by evaporation in conduits 17, 18 and 19 of plate 1 passes upwardly and out through conduit 20 and pipe 22 to the next plate 2.

This excess liquid refrigerant carried with it in solution the circulating oil. Any tendency of the oil to concentrate locally in any of the conduits of plate 1 is overcome by the constant renewal of refrigerant liquid of high density and low in oil concentration fed into the bottom of

conducts 17, 18 and 19 of plate 1, and by the rapid upward velocity of the combined refrigerant liquid and vapor in said conduits.

The mixture of excess liquid and vapor passes out through conduit 20 of plate 1 and pipe 22 to plate 2 where the same process is repeated. A considerable number of such plates as 1 may be refrigerated in series in this manner without excessive pressure drop, and without building up oil concentrations in any of the plates 1, 2 and 3.

A wire 65 of predetermined diameter is inserted in tubing or pipe 60 at fitting 66, whereby to compensate for variation in the internal diameter of said pipe 60. Furthermore, varying the length of wire 65 in pipe 60 will permit of adjustment of the restrictive effect of said pipe 60. Placing the major portion of the restrictive effect near the outlet of pipe 60 increases the thermal efficiency thereof by preventing the vaporization of any of the refrigerant liquid throughout the major portion of tube 60.

It will be observed that plate 3 and accumulator plate 45 are connected by pipe 49.

Having thus described my invention what I claim as new and desire to secure by Letters Patent is as follows:

In a refrigeration plate cooling unit, an evaporator plate comprising a flat plate, an embossed plate superimposed on and secured to said flat plate for forming conduits therebetween, one of said embossments forming an outlet manifold,

an outlet fitting for the outlet manifold positioned adjacent an edge of the evaporator plate, another of said embossments forming a manifold parallel to and spaced from the outlet manifold, still other of said embossments forming parallel conduits some of which connect the second mentioned manifold to the outlet manifold, an inlet fitting positioned adjacent said edge, one of said parallel conduits connecting said inlet fitting with the second mentioned manifold, a by-pass formed by certain of said embossments, said by-pass extending obliquely from said one conduit and connecting the same with the discharge portion of the adjacent parallel conduit, whereby when the evaporator plate is in a vertical operating position the by-pass will operate to permit refrigerant vapors to pass from the upper part of said one parallel conduit to the outlet manifold.
